(57) **CLAIM**

I claim the ornamental design for a water filtration system, as shown.

DESCRIPTION

FIG. 1 is a left side front perspective view of one embodiment of a water filtration system;

FIG. 2 is a right side rear perspective view thereof;

FIG. 3 is a left side view thereof;

FIG. 4 is a right side view thereof;

FIG. 5 is a front elevated view thereof;

FIG. 6 is a rear elevated view thereof;

FIG. 7 is a top plan view thereof;

FIG. 8 is a bottom plan view thereof;

FIG. 9 is a left front perspective view of a further embodiment of a water filtration system;

FIG. 10 is a right side rear perspective view thereof;

FIG. 11 is a left side view thereof;

FIG. 12 is a right side view thereof;

FIG. 13 is a front elevated view thereof;

FIG. 14 is a rear elevated view thereof;

FIG. 15 is a top plan view thereof; and,

FIG. 16 is a bottom plan view thereof.

The broken lines in the drawings are for illustrative purposes only and form no part of the claimed design.
